UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON HEELS.

1,177,784.

Specification of Letters Patent.

Patented Apr. 4, 1916.

Application filed August 2, 1913. Serial No. 782,628.

To all whom it may concern:

Be it known that I, THOMAS LUND, a citizen of the United States, residing at Beverly, in the county of Essex and State of Massachusetts, have invented certain Improvements in Machines for Operating on Heels, of which the following description, in connection with the accompanying drawings, is a specification, like reference characters 10 acting on the drawings indicating like parts in the several figures.

This invention relates to machines for operating on heels and is herein shown as embodied in a heel nailing machine although its application is not limited to such machines but may extend to any machines wherein it is desired to operate obliquely with tools upon a heel.

In presenting a heel to the operation of drivers or awls, for example, it is customary to hold the heel under pressure between a jack and a die plate through the latter of which the drivers or awls reciprocate. Heretofore the jack has been movable in horizontal ways regardless of whether the work engaging surfaces of the jack and die plate were horizontal or not. A very large proportion of heels now in use are pricked obliquely and attached by nails driven at an inclination toward the rear of the heel and this is effected by holding the heel obliquely in the path of the drivers or awls. The work engaging surface of the jack and die plate are consequently disposed at an inclination to the guideways in which the jack is mounted. This arrangement develops a strain upon the jack post and other machine parts and also has a tendency to displace the jack upon its ways.

One object of the present invention is to improve the conditions above set forth.

An important feature of the invention consists in arranging the ways for the jack at an inclination corresponding to that of the work engaging face of the die plate. This expedient eliminates all tendency to displacement of the jack when subjected to pressure. In fact, when pressure is applied to a jack mounted in guideways which are inclined upwardly from a point in alignment with the path of the tools the application of pressure to the jack tends strongly to hold it in its operative position, or move it to that position if slightly displaced.

Another feature of the invention consists in the provision of a jack having its work supporting post disposed at an inclination to that portion of its base which slides in the inclined guideways. By employing such construction the jack post may be made to stand parallel to the line in which pressure is applied to the work and consequently all bending strains are eliminated both in the jack post and in the machine parts which carry the jack support.

These and other features of the invention will be best understood and appreciated from the following description of a preferred embodiment thereof selected for purposes of illustration and shown in the accompanying drawings, in which—

Figure 1 is a view in perspective of the jack and the associated parts of the machine, and Fig. 2 is a view in section of the parts shown in Fig. 1.

In the accompanying drawings the invention is shown as embodied in a lightning heelng machine similar to that disclosed in United States Letters Patent No. 887,870, granted May 19, 1908, on an application of W. H. Taylor. Only such parts of the machine are herein shown as are necessary to a complete understanding of the present invention. For further details of construction reference may be had to the patent above-identified.

The machine frame 2 has vertical journals in which reciprocate a pair of side rods 4 carrying at their upper end the cross head 6. The driver gang 7 is mounted in a removable driver block carried by the cross head. Secured to the frame beneath the cross head is the stationary die plate 8 having vertical driver passages through which the drivers reciprocate. A heel holding device 19 is located beneath the die plate.

In the lower part of the machine is located a movable jack carriage support 10 upon which the jack carriage 12 is supported through the medium of a quick screw 14. The jack carriage slides in vertical guides formed in part by the gibs 17 and in part by the machine frame to which the gibs are bolted. The screw 14 is rotated either manually or automatically to elevate the jack carriage and jack in measuring the work preliminarily to the application of the attaching pressure. This pressure is se-

cured automatically by elevating the jack carriage support 10 and all the parts carried thereby during the initial portion of the downward movement of the driver gang.

5 The jack carriage support 10 is elevated through the medium of a cam 11 and other mechanism not shown.

In order that the attaching nails may be driven obliquely the work engaging face 9 of the die plate 8 is beveled as shown in Fig. 2 and the jack is so arranged that the heel seat surface of the shoe shall be presented at a corresponding or somewhat greater inclination. The jack carriage 12 is provided with ways 13 which are inclined downwardly toward a point beneath and in alignment with the driver passages and in a direction substantially parallel to the inclined face 9 of the die plate.

10 The jack 20 is provided with a sliding base 21 having laterally extending flanges shaped to fit in the ways 13. The base of the jack 20 is made substantially thicker at its rear end than at its forward end so that its upper surface is substantially horizontal. The body of the jack is drilled vertically to receive the heel post 22. The post 22 is adjustably supported in the jack by a large corrugated nut 23 and has at its 15 upper end an adjustable last plate 26 which can be set in different positions to accommodate lasts of different shapes. An adjustable toe post 24 is pivotally mounted in the forward end of the body of the jack 20 and by the relative adjustment of the two posts 24 and 22 the proper inclination of the shoe sole may readily be secured.

20 Carried by the jack carriage 12 is a pair of counter clamps 30 so arranged as to receive the counter of the shoe to be heeled when the jack is moved rearwardly into its operative position. A back gage or stop 15, also supported on the jack carriage 12, serves to limit the inward movement of the jack by engaging the back of the shoe carried thereon. When properly located the work supporting post 22 will be directly beneath the driver gang 7.

In operation the jack is pulled forwardly 50 into the position shown in Fig. 2 and a shoe is positioned thereon. Meanwhile a heel blank is placed in the holder 19 beneath the inclined face of the die plate 8. The jack is then allowed to move rearwardly carrying the shoe into the position indicated by dotted lines in Fig. 2. The jack carriage 12 is elevated to measure the work and pressure is applied to the work by the elevation of the jack carriage support 10. While this 55 pressure is maintained the driver gang makes a complete reciprocation driving the attaching nail and securing the heel to the shoe. A top lift may be attached by a similar course of procedure. It will be seen that 60 the application of pressure to the jack in

a vertical direction tends to slide the jack toward the rear and so maintains the back of the shoe in close engagement with the back gage 15. On account of the fact that the post 22 is located in direct alignment 70 with the center of pressure and at the extreme rear of the jack carriage support 12, there is no objectionable bending strain imparted to the jack carriage support or to the gibs 17 which guide the support in its 75 vertical movement.

Having thus described my invention, I claim as new and desire to secure by Letters Patent of the United States:

1. A machine for operating on heels having, in combination, a die plate with an inclined work engaging face and vertical tool passages, an inclined guideway for a jack beneath the die plate, and a jack arranged to slide in said guideway and having 80 a vertically disposed work supporting post.

2. A machine for operating on heels having, in combination, a die plate with an inclined work engaging face, a guideway located beneath the die plate and disposed 85 parallel to the work engaging face of the die plate, and a sliding jack having a work supporting post vertically disposed in all positions on the guideway.

3. A machine for operating on heels having, in combination, a vertically moving cross head carrying a gang of tools, a die plate beneath the cross head having a work engaging face disposed at an inclination to the path of the tools, correspondingly inclined guideways, and a jack movable therein and having a work engaging post disposed parallel to the path of movement of the cross head.

4. A jack for a heeling machine comprising an elongated base thicker at one end than at the other, having a substantially horizontal upper surface and an inclined guideway surface at its lower side permitting movement of the jack in an inclined path extending in the general direction of the length of a shoe sustained by the jack, and a jack post rigidly maintained in a position at right angles to the upper horizontal surface of the base.

5. A machine for operating on heels having, in combination, a reciprocatory driver gang, a die plate perforated to receive the drivers of the gang and having a work engaging face inclined relatively to their path of movement, a support having guideways inclined in a direction parallel to the work engaging face of the die plate, and a jack having a sliding base thicker at one end than at the other whereby the jack post is held 110 in a position parallel to the path of the driver gang.

6. A machine for operating on heels having, in combination, a reciprocatory driver gang, a die plate, guideways inclined down- 115

wardly to a point in alinement with the path of the driver gang, and a jack having a sliding base thicker at the rear end than at its forward end, and a post disposed perpendicularly to the upper surface of the base.

7. A machine for operating on heels having, in combination, a reciprocatory driver gang, a die plate, guideways inclined upwardly from a point in alinement with the path of the driver gang, and a jack mounted therein and arranged to move by gravity into operative relation with the driver gang and having its post disposed substantially parallel to the path of the driver gang.

8. A machine for operating on heels having, in combination, a die plate having an inclined face, a jack support having guideways correspondingly inclined, a jack movable in said guideways, means for relatively moving the die plate and support to subject a heel to pressure, and a stop for the jack

so disposed that when pressure is applied the jack tends to press against the stop.

9. A machine for operating on heels having, in combination, a die plate, an oppositely disposed jack support movable relatively thereto to subject a heel to pressure, and a jack transversely slidable with respect to the line of relative movement of the die plate and support to and from operative position in alinement therewith and being so mounted that the application of pressure thereto tends to slide the jack into its operative position and prevent it from being displaced therefrom.

In testimony whereof I have signed my name to this specification in the presence of two subscribing witnesses.

THOMAS LUND.
